(57) **CLAIM**

The ornamental design for a jacquard woven golf ditty bag, as shown and described.

DESCRIPTION

FIG. 1 is a perspective view showing one preferred embodiment of my invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an alternative embodiment of the invention which is identical to the embodiment of FIGS. 1–7, but without a hook.
